UNITED STATES PATENT OFFICE.

WILLIAM J. STEWART, OF CHICAGO, ILLINOIS.

DESIGN FOR A SEWING-MACHINE FRAME OR HEAD.

SPECIFICATION forming part of Design No. 33,812, dated October 2, 1900.

Application filed September 10, 1900. Serial No. 29,611. Term of patent 14 years.

To all whom it may concern:

Be it known that I, WILLIAM J. STEWART, a citizen of the United States, residing at Chicago, in the county of Cook and State of Illinois, have invented and produced a new and original Design for Sewing-Machine Frames or Heads; and I do declare the following to be a full, clear, and exact description of the same, reference being had to the accompanying drawings, forming a part of this specification.

This invention relates to a design for a head or frame for light hand or toy sewing-machines, and my said design consists in the structural configuration hereinafter described and illustrated in the accompanying drawings.

In the accompanying drawings, illustrative of the present invention, Figure 1 is a front elevation; and Fig. 2 a transverse section at line xx, Fig. 1.

As represented in the drawings, the head or frame comprises a main annular body portion 1, having a flattened elliptical outline with the longer axis arranged horizontally, as shown, a supporting base or pedestal 2, ²⁵ connected centrally to the main body portion 1, and a table portion 3, projecting into the space inclosed by the main annular body portion 1.

I claim—

The design for a sewing head or frame, as herein shown and described.

In testimony whereof witness my hand this 5th day of September, 1900.

WILLIAM J. STEWART.

In presence of—

ALEX. W. GRANT,
HENRY A. NOTT.
